UNITED STATES PATENT OFFICE

ANDREW H. STEWART, OF SHIELDS, PENNSYLVANIA, ASSIGNOR TO THE PHOENIX GLASS COMPANY, OF MONACA, PENNSYLVANIA, A CORPORATION OF WEST VIRGINIA

GLASSWARE AND METHOD OF MAKING SAME

Application filed January 24, 1930. Serial No. 423,035.

My invention relates to glassware and the method of making the same and more particularly to lamp globes and the like.

While the invention is capable of use in connection with the manufacture of lamp globes of various types, I have, for convenience of description, herein shown it as applied to the manufacture of so-called "canteen globes" such as are employed at gasoline stations for their decorative effect and as sign displays.

In the making of illuminated signs and decorative globes, it is desirable that the decorative coloring and lettering be applied to the inner walls of the globes so that they will not become worn off through exposure to the weather. In globes of the canteen type, it is difficult to apply coloring to the interior surfaces thereof, because of the restricted opening through which access must be ordinarily had to the interior of the globe.

One object of my invention is to provide means and a method whereby the interior surfaces of canteen globes and the like may be readily decorated.

Another object of my invention is to provide a globe structure of generally improved form.

One manner in which my invention may be practised is shown in the accompanying drawing, wherein Figure 1 is a face view of a globe; Fig. 2 is a sectional view of the structure of Fig. 1; Fig. 3 shows the parts of the structure of Fig. 2 in disassembled relation; Fig. 4 shows a glass plate from which one of the faces of Fig. 2 may be formed, and Fig. 5 is a sectional view thereof.

The globe as a whole is designated by the numeral 6 and is intended to be mounted upon a pedestal and to contain a lamp for illuminating the same, as is common in this art. In the manufacture of the globe, the glass is blown to the general form indicated by Fig. 3, in accordance with common practice in the glass-blowing art. In order to

permit of conveniently decorating the interior of the body portion 7 of the globe along the inner side of its edge wall or rim portion, by paint, for example, as indicated at 8, I cut an opening through one face or side 30 of the body portion 7 as indicated at 9. Preferably I remove substantially the entire face of the body portion 7. The disc or glass thus removed from the globe after it has been blown may be discarded or employed as a 35 face plate for another and perhaps smaller size globe.

By the provision of the enlarged opening through the side of the globe, the inner surface of the rim portion of the globe is made 40 accessible for decorating purposes. Since the completed globe is intended to be illuminated for visibility of display matter carried by the sides of the globe, it is desirable that the rim portion be decorated to control 45 the transmission of light and color there-through with a less degree of intensity than that of the sides, and to serve to set off the display matter on the sides while enhancing 50 the appearance of the globe even when the 70 globe is not illuminated. Such decorations may, of course, be simply a coating of paint 55 of the desired color or may be an elaborate and fanciful design of varied colors, as desired, conveniently applied through the open 75 side of the globe. The interior decorations of the globe will, of course, be visible externally thereof.

The coating of paint 8 can be readily applied through the opening at 9 and this paint 80 may be of either ordinary paint or one of the well-known types of paint that can be burned on after it is applied to the glass.

The face plates 10 and 11 which carry the lettering or the decorations that are to be 85 illuminated by a lamp within the globe have such lettering and decorative coloring applied thereto, preferably while they are in the flat condition as shown in Figs 4 and 5. It is obviously more convenient to apply let- 90

tering to a flat plate than to one that is curved.

The face plates 10 and 11 are then heated to soften them and permit of their being bent to the form shown in Figs. 2 and 3, and may be fired to affix the coloring thereto. The coloring is preferably applied to the inner surfaces of these plates 10 and 11 so that they will not be exposed to the weather.

10 The plates 10 and 11 are fastened in place by cement 12 and by screws or bolts 13.

The side wall 7a of the globe 7 may be removed if desired, but I prefer to retain the same because of the increased strength which 15 it imparts to the globe and because removal thereof is not necessary to permit of decorating the interior of the rim portion of the globe.

The sides or faces of the globe are provided 20 with an annular shoulder at the point of juncture between each side and the rim of the globe, such shoulders being preferably formed by depressing the faces of the globe where they join with the rim. Removal of 25 one of the sides to permit access to the interior of the globe naturally weakens the globe. However, by cementing the edges of the face plates 10 and 11 to the shoulders at 12, the plates serve as bracing members for 30 the rim with practically the same effect as the removed side, thereby restoring substantially the original strength of the globe. I prefer, however, to cut out only a portion of the side of the globe, as shown in Figs. 2 35 and 3, the remaining portion of the cut-out side forming a flange member which serves to stiffen the shoulder and the rim of the globe and, also, serves as a seating surface for the face plate. Such cut-out portion of 40 the side will be of such size as to expose the major portion of the face plate to the interior of the globe. The face plate can then be positioned and supported on the flange member and connected to the shoulder, thus 45 adding to the strength of the structure.

I claim as my invention:

1. A sign globe comprising an all-glass body having a rim portion and side portions, the rim being of circular form and the said 50 body having an annular shoulder formed in each side, at the point of juncture between said rim and said side, one of the said sides being cut away adjacent to the said shoulder to form an opening permitting access to the 55 inner surface of said rim portion, visible decorating material on said surface adjacent to said shoulder, and a face plate covering the said opening and cemented at its edges to the adjacent shoulder.
- 60 2. As a new article of manufacture, a display device, adapted to be illuminated interiorly, consisting of an all-glass hollow globe having a rim portion provided with an open neck formed integrally therewith, 65 disc-like side portions integral with the rim,

one of said sides being cut away along a line adjacent to the edge of the rim to form an opening permitting access to the inner surface of the rim, decorative material applied to the said surface by means introduced through 70 said opening, the decorations being visible through the wall of said rim, and a face plate covering said opening and secured at its edges to the said rim portion, the inner surface of said plate having display characters thereon. 75

In testimony whereof I, the said ANDREW H. STEWART have hereunto set my hand.

ANDREW H. STEWART.
